UNITED STATES PATENT OFFICE.

FÉLIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

LOOPER MECHANISM FOR SHOE-SEWING MACHINES.

1,419,997.

Specification of Letters Patent. Patented June 20, 1922.

Application filed August 1, 1918. Serial No. 247,750.

To all whom it may concern:

Be it known that I, FÉLIX EMILE VALOIS, a citizen of the United States, residing at Haverhill, county of Essex, State of Massachusetts, have invented a certain new and useful Improvement in Looper Mechanism for Shoe-Sewing Machines, of which the following is a specification, reference being had therein to the accompanying drawings.

10 My invention relates to looper mechanism for sewing machines particularly intended for use in the manufacture of boots and shoes. The particular object of the invention is to provide a looper operating mechanism which shall not contain any cams, and which at the same time shall give to the looper a path of movement which will make the looper effective in performing its functions. In the machine shown in the accompanying drawings, eccentrics are employed to operate the looper. This makes it possible to run the machine at much higher speed without noise or jar. In the hereinafter described mechanism the looper is on the end 25 of a bodily movable looper bar and the looper may be considered to have a movement separable into two components, one of which is lengthwise of the looper bar and the other is transversely to it. When considered in this manner, the lengthwise movement is given to the looper by one eccentric while the transverse movement is given to it in part by both eccentrics, but mainly by the second. The two eccentrics are driven 35 by suitable gearing which causes the eccentric which moves the looper bar longitudinally to make two revolutions for each revolution of the other eccentric. The arrangement described not only permits the use of eccentrics instead of cams but gives to the looper the proper motion for cooperating with the other stitch forming instrumentalities, and does away with a looper bar having a long unsupported portion. This is a 40 great advantage in a machine to be run at high speed, since a long looper bar springs and causes a deviation of the looper from the predetermined path of movement as well as produces vibration.

50 My looper operating mechanism also keeps the looper close to the line of thread extending from the work support to the take up during the portion of the cycle of movement of the machine in which the take up is draw-

ing down the thread so that the thread renders easily and without undue strain; and further the path of movement of the looper is such that the looper is kept well away from the upper of the shoe.

The invention will be fully understood 60 from the following description when taken in connection with the accompanying drawings and the novel features thereof will be pointed out and clearly defined in the claims at the close of this specification.

In the drawings, Fig. 1 is a vertical section of a portion of a sewing machine embodying the invention.

Fig. 2 is a front elevation of the parts shown in Fig. 1.

Fig. 3 is a top view of the looper bar and eccentrics.

Fig. 4 is a diagram showing the path of movement of the looper relative to the needle.

Referring now to the drawings, at A is shown the frame of the machine. At B is shown a needle carried by a needle sector C and actuated by a link D, connecting rod E, a crank F and a link G. These parts do not require to be described in detail herein. These parts give to the needle an oscillatory movement about a centre H, the movements being timed to cooperate effectively with the other stitching instrumentalities. At I is shown the work support or table.

At 11 is shown a looper adjustably mounted in the end of a looper bar 12. The end of the looper bar 12 which is away from the looper 11 is formed into an eccentric strap 13 engaging the eccentric 14 mounted on a shaft 15 in the frame of the machine. This eccentric 14 moves the looper bar longitudinally and also cooperates in giving the looper its transverse movement. The transverse movement of the looper is chiefly effected by an eccentric 16 mounted on a shaft 17 which is parallel with the shaft 15. The eccentric 16 cooperates with an eccentric strap 18, the end of which is pivoted at 19 to the looper bar at a point intermediate the eccentric 14 and the looper 11.

At 20 is shown the main shaft on which is mounted a master gear 21. A gear 22 on a cross shaft 23 meshes with the master gear 21 and the cross shaft carries a bevel gear 24 which meshes with the bevel gear 25 on the eccentric shaft 15. The master gear 21

and the bevel gear 22 have a ratio of two to one while the gears 24 and 25 are of equal size so that the eccentric shaft 15 makes two revolutions for each revolution of the master gear 21. On the side of the master gear 21 opposite to the bevel gear 22 is located another bevel gear 26 which is of the same size as the bevel gear 22. The gear 26 is mounted on a cross shaft 27 on which is a spiral gear 28 meshing with a spiral gear 29 on the eccentric shaft 17. The spiral gears 28 and 29 are designed so that the eccentric shaft 17 makes one revolution for every two revolutions of the eccentric shaft 15.

From the foregoing it will be seen that the looper bar is given two longitudinal movements for each transverse movement. This produces a peculiar movement of the looper in a closed path or orbit having a reentrant loop.

The path of movement of the looper has been plotted in Fig. 4 of the drawings, and the position which the looper occupies at the end of each 45 degree movement of the master gear has been indicated, successive positions being serially numbered. The feed of the work is in the direction of the large arrow in Fig. 4 and looper travels in the direction indicated by the small arrow.

The position marked 8 is the position occupied by the looper when the needle is near the top of its stroke. The needle goes down at about the position marked 2 and the looper in moving around the curve 2, 3, 4 lays the thread in the barb of the needle. As the needle-loop is being passed around the shuttle, the looper is projected forwardly so that at the time the take-up action occurs, the looper is rounding the end of the reentrant loop at the point 6 and, in rounding the end of such loop is maintained substantially in line with the lead of the thread from the work to the take-up, during the take-up action. At the completion of the take-up action the looper is withdrawn to the position 8 to get it out of the way of the advancing awl.

The mechanism described may be run at very high speed as the two eccentrics give to the looper an easy motion and at the same maintain the looper in the positions relative to the needle best calculated for the rapid formation of the stitch.

What I claim is:

1. A sewing machine having, in combination, a hooked needle, a take-up, a looper at the same side of the work as the take-up, and eccentric means for moving said looper in a closed path having a reentrant loop, substantially as and for the purposes specified.

2. A sewing machine having, in combination, a hooked needle, a take-up, a looper at the same side of the work as the take-up,

and means comprising a plurality of eccentrics for moving said looper in a closed path having a reentrant loop, substantially as and for the purposes specified.

3. In combination, a looper, a looper bar, means to move the looper bar longitudinally, means to move the looper bar transversely said means being timed so that the looper bar is given twice as may longitudinal movements as transverse movements.

4. In combination, a needle, needle actuating mechanism, a looper, a looper bar, means to move the looper bar longitudinally, means to move the looper bar transversely, said means being timed so that for each complete cycle of movement of the needle, the looper bar will be given two complete longitudinal movements and one complete transverse movement, and the looper will travel in a closed path having a reentrant loop which includes the needle within its limits.

5. In combination, a needle, needle actuating means, a looper, a looper bar, means to move the looper bar in a line parallel to the plane of movement of the needle, means to move the looper bar in a plane substantially at right angles to the plane of movement of the needle, said means being timed so that the looper bar will make two movements parallel to the plane of the needle and one movement in the plane at right angles for each cycle of the needle, and the looper will travel in a closed path having a reentrant loop at right angles to the plane of the needle.

6. In combination a looper, a looper bar, a rotary member to give the looper bar a longitudinal movement, and a rotary member to give the looper bar a transverse movement, said members being timed to give two longitudinal movements to the looper bar for each transverse movement thereof.

7. In combination, a looper, a looper bar, and two eccentrics to actuate said looper bar, one of said eccentrics being connected to said looper bar at the end away from the looper and giving to the looper bar a longitudinal movement and the other eccentric acting on said looper bar at a point intermediate the looper and the first mentioned eccentric.

8. In combination, a looper, a looper bar, and two eccentrics to actuate said looper bar, one of said eccentrics being connected to said looper bar at the end away from the looper and giving to the looper bar a longitudinal movement and the other eccentric acting on said looper bar at a point intermediate the looper and the first mentioned eccentric, said eccentrics being timed so that the second mentioned eccentric will make one revolution to two revolutions of the first eccentric.

9. In combination, a looper, a bodily movable looper bar, an eccentric connected to said looper bar at the end away from the looper, a second eccentric, and an eccentric

strap therefor connected to the looper bar at a point intermediate the ends of the looper bar.

10. In combination, a looper, a looper bar, an eccentric connected to said looper bar at the end away from the looper, a second eccentric, and an eccentric strap therefor connected to the looper bar at a point intermediate the ends of the looper bar, said eccentric being timed so that the last mentioned eccentric will make one revolution for each two revolutions of the first eccentric.
11. In combination, a looper, a looper bar, an eccentric, an eccentric strap rigidly connected to that end of the looper bar which is at a distance from the looper so that the eccentric both swings the looper bar and acts as a pivot, a second eccentric, an eccentric strap therefor, said strap being connected to the looper bar at a point intermediate its ends, so that it swings the looper bar about the first eccentric as a pivot, and gives the looper a movement transverse to that given it by the first eccentric.
12. In combination, a looper, a looper bar, an eccentric connected to said looper bar at the end away from the looper, a second eccentric acting on the looper bar at a point intermediate its ends, shafts for said eccentrics, and gearing actuating said shafts so that one eccentric makes two revolutions to each revolution of the other eccentric.
13. In combination, a looper, a looper bar,

an eccentric connected to said looper bar at the end away from the looper, a second eccentric acting on the looper bar at a point intermediate its ends, parallel shafts for said eccentrics, a master gear, two to one gearing between the master gear and the eccentric connected to the end of the looper bar, and one to one gearing between the master gear and the other eccentric.

14. In combination with stitch-forming instrumentalities including a hooked needle, a looper, a looper supporting bar movable endwise and sidewise and disposed transversely of the hooked end of the needle when the latter is in loop-receiving position, mechanism including an actuating eccentric for moving the looper bar endwise and sidewise to lay a loop of thread in the hook of the needle, said mechanism being constructed and arranged to move the looper in time with the other stitch-forming instrumentalities in a closed curve path.

15. A sewing machine having, in combination, stitch-forming mechanism including a hooked needle, a looper, a plurality of eccentrics connected to run at different speeds, and operative connections between said eccentrics and looper for moving the latter in a closed path.

In testimony whereof I affix my signature.

FÉLIX EMILE VALOIS.
